UNITED STATES PATENT OFFICE.

THOMAS MACDONALD, OF LONDON, ENGLAND.

PANTOGRAPHIC APPARATUS.

1,229,111.

Specification of Letters Patent.

Patented June 5, 1917.

Application filed February 24, 1916. Serial No. 80,321.

To all whom it may concern:

Be it known that I, THOMAS MACDONALD, a subject of the King of Great Britain, residing at London, England, have invented 5 certain new and useful Improvements in Pantographic Apparatus, of which the following is a specification.

This invention relates to pantographic apparatus for drawing, engraving or other 10 purposes, and in which a plane or table is attached to the pantograph, and is moved by the pantograph in such a way that the motion of the tracing point or its equivalent is reproduced in every point of such plane or 15 table, thus replacing the drawing point of a pantograph by a drawing surface, plane or table, for the purpose of increasing the usefulness of the pantograph.

According to the invention the plane or 20 table is mounted upon cross traveling frames and its movements take place under the restraint of controllers as herein described, and means are provided by which the controllers are kept taut at all linked and pivoted parts, 25 whereby the efficiency of the apparatus is increased both in regard to the operation and the quantity and variety of working usefulness.

In order to still further increase the efficiency and usefulness of the apparatus 30 means are provided for positioning the tool so that it will work upon any desired part of the plane or table. These means comprise a radial bar pivoted on the frame of 35 the machine above the level of the plane or table, and upon the bar slides the holder of a positioning point linked to a sliding tool carrier, so that when the positioning point is moved to any position the tool is moved 40 to a corresponding position on the plane or table.

The tool may work downward upon the plane or table to produce copies similar to the master patterns or designs or it may 45 work upward beneath an elevated table fixed upon the plane or table controlled by the pantograph, to reverse the designs.

In the accompanying drawings:—

Figure 1 is a plan showing the positions 50 of the plane or table in relation to the pantograph and also the radial bar for positioning the tool.

Fig. 2 is a side elevation of the apparatus.

Fig. 3 is a plan of the cross traveling 55 frames for supporting the plane or table and

the controllers or link motion for controlling the movements of the same.

Fig. 4 is a side elevation of the cross traveling frames, showing the plane or table mounted thereon.

60

Fig. 5 is a plan of the lower frame.

Fig. 6 is a plan of the middle frame and controllers.

Fig. 7 is a plan of the upper frame and controllers, to the upper part of which frame 65 the plane or table is fixed.

In the apparatus illustrated the main framework *a*, supports at one end a fixed pivot or fulcrum *b* for a pantograph *c* which has a tracing point *d*, intended to be moved 70 over the master pattern or model *e* which in the example shown happens to be a letter placed on a fixed table *f* and hereinafter referred to.

A plane or table *g* which carries the plate 75 to be engraved or drawn upon is connected to the pantograph so that all points on its surface will make movements corresponding to the movements of the tracing point *d*. The table *g* is mounted on three studs 12 on 80 an upper frame *C* which is attached to the pantograph *c*, by a link *h* and pin *i*, the link *h* being pivotally connected to the frame *C* between centers or screws *k*.

In order that the table *g* may move in its 85 own plane in all directions the upper frame *C* is mounted on a middle frame *B* so that it can move from left to right thereon, and in turn the middle frame *B* is mounted on a lower stationary frame *A* so that it can 90 move back and forth thereon. Anti-friction rollers *l* are provided on the middle frame *B* for the upper frame *C* and similar rollers *m* on the lower frame *A* for the middle frame *B*.

95
To insure that the frames *B* and *C* shall each make definitely straight line motions relatively to the frame supporting it, controllers or parallel link motions are provided. The controllers for the frame *B* consist of levers *n*, pivoted to the lower stationary frame *A* at *o*, and connected in pairs by links *p* which are pivotally connected to the frame *B* at *q*.

The controllers for the upper frame *C* 105 consist of levers *r* pivoted at *s* to the frame *C* and connected in pairs by links *t* pivotally connected to the frame *B* at *u*.

The parallel controllers are kept taut at all their linked and pivoted parts, and 110

friction is reduced, by rollers *v* and *w*, which rest upon loose angle bars *x* and *y*, respectively, so as to be capable of rolling along them. The bars *x* and *y*, are supported at their ends by the frames A and B respectively, the bars being free to slide thereon. The rollers *v* bear against a bar 2 fixed on or formed integrally with the frame B being pressed there-against by screws 3 passing through lugs 4 on a bar 5 of the stationary lower frame A, the screws bearing against springs 6 which in turn press against the loose angle bar *x*. Similarly, the rollers *w* bear against a bar 7 fixed on or formed integrally with the upper frame C, being pressed there-against by screws 8, passing through lugs 9 on a bar 10 on the frame B, the screws bearing against springs 11 which in turn press against the loose angle bar *y*. The rollers *v* and *w* lie on their lower faces on the lower flanges of the respective bars or angle irons *x* and *y*, but are also gripped at their peripheries between the vertical flanges of said bars or angle irons and the bars 2 and 7, so that they are not found to be displaced from their proper positions in practice. Similarly the pressure transmitted by the screws 3 and 8 holds the bars or angle irons in proper position. If desired as an additional safe guard the rollers *v*, *w*, might be grooved to receive the adjacent edges of the bars 2 and 7 and a rail on the bars *x*, *y*. Such a modification is indicated in Fig. 4 wherein the roller *v*, is shown grooved, and the bar *x* has a corresponding rail *x'*.

Referring to Figs. 1 and 2, a radial bar 14 is pivoted at 15 and carries two sliding holders 16, 17. The holder 16 is fitted with a lower engraving or drawing tool 18, and in some cases with an upper tool 19. The tool 18 is used for engraving or drawing upon the table *g* an exact reproduction of the design to be copied, whereas the tool 19 engraves or draws upon the underside of an elevated table 20 mounted on columns 21 on the table *g*, so as to reproduce reverse designs. The sliding holder 17 carries the positioning point 22. The carriers 16, 17, are linked together by links 23, so that when the positioning point 22 is moved to any desired position on a diagram of positions or templet of the work to be reproduced placed on the fixed table 13, the tools 18, 19, are moved into a corresponding position relatively to the tables *g* and 20 for the work.

Thus, for example, assuming that the word "Engraved" is to be engraved or drawn on a plate, a diagram of positions or templet of the work is placed on the fixed table 13. It is not necessary that this diagram shall be a complete design as it need only be a sheet of proper size divided into

sections by cross lines or having any other convenient indications of the positions required. It being ascertained in which section or position the word "Engraved" is situated the positioning point 22 is moved to this section or position so that the tools 16, 17, are moved to corresponding positions on and below their respective tables. A rough outline of the word is placed on the table *f*, as indicated at 24. A zinc or other model of each letter of the word is then taken in turn and placed on the table *f* in line with its corresponding letter on the outline 24. For instance a perfectly formed model *e* of the letter G is shown, its position being conveniently determined by a T square 25 running on a straight edge 30. The tracing point *d* is then moved over the model *e*, so that the letter is reproduced by the tool 16 on the table *g*, or a reverse reproduction is made by the tool 17 on the table 20. The word "Engraved" is shown in dotted lines in Fig. 1 reproduced in two different positions. The positions of the pantograph *c* and links 23, assumed for two different positions of the tracing point *d* are also indicated in dotted lines.

When it is desired to engrave or draw ornamental borders or like work a number of tools 26 may be carried by holders 27 which may be fixed or adjustably held in position.

I claim:—

1. In pantographic apparatus of the kind referred to, a stationary base frame and two cross traveling frames superposed thereon, controllers for linking the two cross traveling frames together, and other controllers for linking the lower of the cross traveling frames to the stationary base frame, a table mounted on the upper of the said traveling frames, and means for holding a working tool above said table, substantially as and for the purpose hereinbefore set forth.

2. In pantographic apparatus of the kind referred to, a stationary base frame and two cross traveling frames superposed thereon, controllers for linking the two cross traveling frames together, and other controllers for linking the lower of the cross traveling frames to the stationary base frame, a table mounted on the upper of the said traveling frames, means for holding a working tool above said table, and means for positioning said tool relatively to said table, substantially as hereinbefore set forth.

3. In pantographic apparatus of the kind referred to, a stationary base frame and two cross traveling frames superposed thereon, controllers for linking the two cross traveling frames together, and other controllers for linking the lower of the cross traveling frames to the stationary base frame, a table

- mounted on the upper of the said traveling frames, means for holding a working tool above said table and means for insuring the taut control of the movements of the frames
- 5 with little friction during the parallel travel thereof, comprising two loose bars, one carried by the base frame and the other by the lower cross traveling frame, bars fixed on the base frame and lower cross traveling
- 10 frame, loose rollers between and in contact with said loose bars and fixed bars, and resilient and adjustable means for maintaining said rollers in contact with said bars, substantially as hereinbefore set forth.
- 15 4. In pantographic apparatus of the kind referred to, a stationary base frame and two cross traveling frames superposed thereon, controllers for linking the two cross traveling frames together, and other controllers
- 20 for linking the lower of the cross traveling frames to the stationary base frame, a table mounted on the upper of the said traveling frames, means for holding a working tool above said table and means for insuring the
- 25 taut control of the movements of the frames with little friction during the parallel travel thereof, comprising two loose bars, one carried by the base frame and the other by the lower cross traveling frame, bars fixed on
- 30 the base frame and lower cross traveling frame, loose rollers between and in contact with said loose bars and fixed bars, and resilient and adjustable means for maintaining said rollers in contact with said bars,
- 35 consisting of screws carried by the lower cross traveling frame and the base frame, and springs between said screws and the aforesaid loose bars, substantially as and for the purpose hereinbefore set forth.
- 40 5. In pantographic apparatus of the kind referred to, a stationary base frame and two cross traveling frames superposed thereon, controllers for linking the two cross traveling frames together, and other controllers
- 45 for linking the lower of the cross traveling frames to the stationary base frame, a table mounted on the upper of the said traveling frames, means for holding a working tool above said table, means for
- positioning said tool relatively to said table, 50 comprising a pivoted radial bar situated above the level of the table, a carrier for the working tool and another carrier having a positioning point, said carriers being slidably mounted on said radial bar, and links 55 connecting said carriers for insuring movements of the same in unison, substantially as and for the purpose hereinbefore set forth.
6. In pantographic apparatus of the kind referred to, a stationary base frame and 60 two cross traveling frames superposed thereon, controllers for restraining and linking the two cross traveling frames together and other controllers for restraining and linking one of the cross traveling frames to the stationary base frame, a table mounted on the other of the said traveling frames, and means for holding a tool for working upon and above the said table, substantially as and for the purpose hereinbefore set forth. 70
7. In pantographic apparatus of the kind referred to, a stationary base frame, two traveling frames superposed thereon and movable at right angles to the other, controllers pivoted intermediate their ends to 75 one of said traveling frames and pivoted at their outer ends to the other of the traveling frames for restraining and linking the two traveling frames together, other controllers pivoted intermediate their ends to 80 one of the traveling frames and having their opposite ends pivoted to the stationary frame for restraining and linking one of said traveling frames to the stationary base frame, a table mounted on the other of the 85 said traveling frames, and means for holding a tool above the said table, an elevated table mounted on the aforesaid table, and means for holding a tool below the said elevated table for reversing designs, substantially as hereinbefore set forth. 90

In testimony whereof I have signed my name to this specification in the presence of two subscribing witnesses.

THOMAS MACDONALD.
